SHIELD FOR PORTABLE ACETYLENE-GAS LAMPS

1,093,128.

Specification of Letters Patent. Patented Apr. 14, 1914.

Application filed July 10, 1912. Serial No. 703,559.

To all whom it may concern:

Be it known that I, AUGIE L. HANSEN, a citizen of the United States, residing at Chicago, county of Cook, and State of Illinois, have invented a certain new and useful Improvement in Shields for Portable Acetylene-Gas Lamps, of which the following is a specification.

My invention relates more particularly to lamps of this type which are used by miners. It is very frequently the case that where miners are working in pairs that the eyes of the adjacent miner are dazzled by the light, while the intense whiteness of the

15 flame is injurious to the eyes.

My invention has for its object to provide a shield which can be detachably secured to the reflector of an acetylene gas lamp and which will be rotatably mounted thereon, 20 permitting the user of the lamp to shift it in its position, so as to shield his fellow worker whether he is on one side or the other.

My means of accomplishing the foregoing 25 may be more readily understood by having reference to the accompanying drawings, which are hereunto annexed and are a part of this specification, in which:

Figure 1 is a side elevation of an acetylene gas lamp having my improved shield 30 mounted thereon. Fig. 2 is a front elevation of the same. Fig. 3 is a front view of the reflector, showing the shield turned to protect the eyes of the worker at the side of the 35 user of the light. Fig. 4 is a front elevation of a modified form of my invention. Fig. 5 is a vertical section of the same.

Similar reference numerals refer to similar parts throughout the entire description. 40 As shown in the drawings, the shield 1 is secured to the reflector 2 of the lamp, which consists in this instance of a water chamber 3 and a carbide receptacle 4, a burner tip 5 being provided in the center of the reflector 2.

The shield 1, as shown in Figs. 1, 2 and 3, 45 is formed of an annular piece of metal provided with an outwardly extending portion 12, which extends much farther out than the remaining portion of the shield.

The annular member, which preferably is 50 slightly flared, is secured to the body of the lamp by three spring clamps 6, 7 and 8, which, as shown, are secured to the side wall 55 of the shield by means of rivets 9 or any

other suitable form of fastening may be employed if desired.

The outer end of the fastening device is offset, as at 10, and the springiness of the metal forming the clamps 6, 7 and 8 is such 60 that when sprung over the shoulder 11 formed by the reflector 2 joining the body of the lamp, the shield will be securely held in position, but at the same time it is free to be rotated to the position in Fig. 3 in 65 which the outwardly extended portion 12 of the shield will effectually guard the eyes of the operator on that side of the user of the light.

Should the helper be working on the other 70 side of the miner, it is a comparatively simple matter to rotate the shield in the other direction until the outwardly extended portion 12 is in the opposite position to that shown in Fig. 3, as the clamping members 75 serve only to hold the shield in position, but do not interfere with its rotation.

By arranging the clamping members as shown, in the event of the operator striking 80 his lamp against a projection, instead of the shield being crushed, the spring clamps yield and the shield is detached from the body of the lamp without injury to either. This feature is especially desirable where 85 used in mines.

As shown in Figs. 4 and 5, the shield is provided with a concave portion 13, which is provided with a central opening 14, the edges of which are inturned, as at 15, and are adapted to engage the gas tube in which 90 the burner tip is mounted. Four slots 16 are cut in the concave portion 13 of the shield where this type is used, this serving the double purpose of permitting the shield to be detached easily from the lamp by 95 means of a blow in the event of striking a projection, as above referred to, and also serves to afford sufficient pressure due to the springiness of the material used to hold the shield in position. Where this type of shield 100 is employed the concave portion of the shield acts as the reflector of the lamp.

The operation of the device will be fully 105 understood by persons skilled in the art from the foregoing description, but although I have shown a specific form of lamp, I do not limit myself to this form, for my shield is applicable to any carbide lamp employing a reflector and a centrally disposed burner tip.

Having described my invention, what I regard as new and desire to secure by Letters Patent is:

The combination with a lamp provided with a reflector having a central burner, of a shield comprising an annular flaring portion, one side of which extends outwardly beyond the rest of the annular portion and

means to detachably and rotatably secure the said shield to the reflector.

In witness whereof I have signed the foregoing specification.

-AUGIE E. HANSEN.
